tion, Ann Arbor, Mich., a corporation of Michi-
gan

Application December 15, 1937, Serial No. 179,999

7 Claims. (Cl. 137—139)

This invention relates to internal combustion engines, and more particularly to a fuel flow governing device for incorporation in the carburetor of an internal combustion engine and adapted to be actuated in response to the flow of fuel mixture through the carburetor to govern the speed of the engine. Stated differently, it may be said that the present invention relates to a carburetor for internal combustion engines, in which the ordinary throttle valve is supplanted by a flow-responsive governor valve.

It is a general object of the present invention to provide a device of the character described in which the governor valve, which is employed in place of the usual throttle valve, is controlled by means which are adjustable to provide for varying the predetermined governed speed.

A further object of the present invention is the provision of a device of the character described, in which the aforesaid adjustment may be carried out by remote control, as for example, by means located on the instrument board of a vehicle.

Another object of the present invention is the provision of a device of the character described, in which the carburetor valve is urged toward closed position by the usual resilient means, the connection between such resilient means and the carburetor valve being such that the closing effort of the resilient means may be opposed by the operator without permitting the operator to directly open the carburetor valve, the latter being thus permitted to function as a governing valve and being subject only to the influences which automatically cause it to act as such.

Other and further objects, features and advantages of the present invention will be apparent from the following specification, taken in connection with the accompanying drawing in which:

Figure 1 is a schematic view illustrating the mode of application of the present invention to a vehicle powered by an internal combustion engine;

Figure 2 is a vertical longitudinal section through the valve control mechanism of the present invention; and

Figure 3 is a vertical transverse section on line 3—3 of Figure 2.

In order to facilitate an understanding of the invention, reference is made to the embodiment thereof shown in the accompanying drawing and detailed descriptive language is employed. It will nevertheless be understood that no limitation of the invention is thereby intended and that various changes and alterations are contemplated

such as would ordinarily occur to one skilled in the art to which the invention relates.

Referring to Figure 1, a portion of the intake manifold of an internal combustion engine is designated by the reference character 10, and is 5 adapted to be supplied with fuel mixture by a carburetor indicated generally at 11. The latter may be conventional in all respects except as to the valve means for controlling the flow of fuel mixture, now to be described.

In place of the usual manually controlled throttle valve heretofore employed in carburetors, the present invention contemplates the use of a governing valve adapted to be controlled in response to the flow of fuel mixture through the conduit 15 with which it is associated. Such valve may be of several known types, but in the present embodiment it is preferred to employ a valve of the type known as the "unbalanced" or "offset" butterfly valve. Thus, in place of the usual manually controlled balanced butterfly throttle valve, there is provided in the fuel mixture conduit 12 of the carburetor 11, an unbalanced butterfly valve 13, secured upon a spindle 14, which latter is journaled transversely of the conduit 12 and is 20 provided with a laterally extending portion 14'. It will be noted that the valve 13 is secured to the spindle 14 in such a manner that its longer blade 15 extends away from the intake manifold 10 and thus extends upstream with regard to the 30 flow of fuel mixture which is intended to be downward in all views. As is well understood, by this construction the valve is adapted to be urged in closing direction by the flow of fuel mixture through the conduit.

This closing effort upon the valve 13 is opposed by a spring 16 associated with the extension 14' of the valve spindle 14 by means of a cam 17 and flexible tape 18. The cam 17 is secured upon the extension 14' of the valve spindle, and one end of the flexible tape 18 is secured to the cam 17 as at 19. The other end of the flexible tape 18 is secured to the adjacent end of the spring 16 in any suitable manner. The spring 16 and its associated mechanism are arranged in the casing 11' 45 associated with the carburetor 11. The tape 18 passes over the surface of the cam 17 so that the force of the spring 16 is applied through varying radii to resist the closing effort on the valve 13. The shape of the cam 17 is carefully determined 50 for the particular characteristics of the engine with which the present device is to be used. The end of the spring 16 opposite to that attached to the tape 18 is anchored by adjusting mechanism comprising an adjusting screw 20 the 55

- inner end of which is provided with a head 21 which is threaded to receive one or more convolutions of the spring 16. The screw 20 is threaded into a nut 22 rotatably mounted in a restricted portion of the casing 11', and means are provided for rotating the nut 22 to effect longitudinal movement of the screw 20, whereby the tension of the spring 16 may be varied to effect the proper initial adjustment thereof. Means are also provided whereby the screw 20 may be rotated so that, as it advances to the right, its head 21 advances into the convolutions of the spring 16, thus varying both the tension and the flexibility of the latter.
- 15 The pitch of the threads of the screw 20 and nut 22 is greater than the pitch of the thread on the head 21, whereby when the adjusting screw 20 is advanced to the right, by suitable rotation, the head 21 moves into the coils of the spring 16 at a 20 slower rate than it advances to the right, so that the tension of the spring 16 is reduced as its rate is increased.

For every speed of the engine for which it is desired to have governing, there is a definite tension and flexibility of the spring which must be effected. The adjustment just described provides for such change in the rate and tension of the spring, for the whole is designed with a predetermined pitch to the threads on the nut 22 and 30 on the screw 20 to assure the proper rate and tension for each of the speeds for which the governor is adaptable. However, during the assembly of the governor and sometimes in later adjustments, it is essential that the initial tension be properly 35 set so that thereafter the tension and rate vary in the predetermined manner.

This is simply effected by rotation of the nut 22 which allows the screw 20 to be moved longitudinally without rotation, thus changing only the 40 tension of the spring. The periphery of the nut, intermediate its ends, is provided with a suitable thread for cooperation with the threads of a screw 39. Rotation of this screw, by a suitable tool, imparts slow rotation to the nut 22, and thus 45 permits minute adjustments of the tension of the spring 16.

The means for rotating the screw 20 are described in detail in my copending application, Serial No. 131,448, now Patent No. 2,170,744, granted 50 Aug. 22, 1939, of which the present application is a continuation-in-part, and need not be further described herein. As disclosed in said previous application, the adjustment of the spring 16 may be carried out from a remote point, such as the operator's compartment, the adjustments of the screw 20 being effected through the medium of a flexible member 23 which may be extended to a suitable terminal 24 located upon the instrument board of the vehicle, and if desired the terminal 24 may take the form of a key-operated locking device, whereby unauthorized adjustment of the governed speed is prevented. Connection between the flexible member 23 and the adjusting screw 20 is effected by providing the adjacent end of the 55 member 23 with a non-circular portion 41 for sliding engagement with a mating recess 42 formed in the screw 20. As fully explained in my said copending application, the provision of means for varying both the tension and the flexibility of the 60 spring 16 enables accurate control of the governing valve at a plurality of predetermined speeds, thus permitting authorized persons to adjust, at will, the governing means for any desired speed within a reasonable range, without 65 destroying the accuracy of governing.

As also fully explained in said previous application, the spring 16, through the cam 17 and tape 18, is adapted to substantially balance the closing effort exerted by the flow of the fuel mixture upon the valve 13, at the predetermined speed and at all positions of the valve, thus ensuring accurate governing of the engine speed. 5

In employing a governor valve of the nature described, in place of the ordinary carburetor valve, means must be provided whereby the governing valve may be closed at the will of the operator, just as the ordinary throttle valve may be closed at the will of the operator. This result is achieved, in the present construction, by the arrangement now to be described. 10

The toeboard 25 of the operator's compartment is provided with the usual accelerator pedal 26 which is connected with a lever 27 by means of a link 28. The lever 27 is pivoted as at 29 to any suitable portion of the vehicle, and its 20 outer end is connected to a relatively strong helical spring 30, the other end of which is secured to the toeboard 25 as by means of a hook 31. The lever 27 is also connected by a link 32 with a lever 33 secured upon a short shaft 34 journaled 25 in the cover 40 of the casing 11'. To the opposite end of the shaft 34 there is secured an arm 35 having a horizontal portion 36. The latter is adapted to engage an arm 37 secured adjacent the outer end of the extension 14' of the valve 30 spindle 14.

From the foregoing description, it is believed that the operation of the instant device will be readily appreciated. When the accelerator pedal 26 is depressed and the spring 30 thus extended, the link 28, lever 27, link 32 and arm 33 will be moved toward the right (Fig. 1), rotating the shaft 34 and arm 35 counterclockwise. Thus, the horizontal portion 36 of the arm 35 is removed from engagement with the arm 37 secured upon 40 the valve spindle, and the latter is permitted to rotate counterclockwise, under the influence of the spring 16, to an extent corresponding to the movement of the accelerator pedal. The governor valve is thus opened and fuel mixture is 45 permitted to flow into the intake manifold, the quantity of mixture being limited in accordance with the position of the valve. As the engine speed increases, the valve is urged toward closed 50 position by reason of the flow of fuel mixture through the conduit, and if the predetermined maximum speed is reached the turning effort on the valve will likewise be increased so as to overcome the resistance of the spring 16, whereupon 55 the valve will close to such an extent as to prevent further acceleration of the engine. If now, the operator desires to slow the engine below the governed speed, the force exerted on the accelerator pedal is reduced, whereupon the spring 30 will draw the lever 27, link 32 and arm 33 to the 60 left, causing a clockwise rotation of the shaft 34, and arm 35. The horizontal portion 36 of the latter will thus be brought into engagement with the arm 37, causing a clockwise rotation of the 65 valve spindle 14, and partially or entirely closing the valve, as the case may be. It will be appreciated that the spring 30 is necessarily strong enough to overcome the spring 16 at all times except when the spring 30 is opposed by force 70 exerted upon the accelerator pedal.

From the foregoing, it will be seen that the operator of the vehicle may at any time permit the spring 30 to close the valve, but cannot directly open the valve or permit it to open beyond 75

the extent dictated by the predetermined speed adjustment.

Having thus described the invention, what is claimed as new and desired to be secured by Letters Patent is:

1. In a governor for internal combustion engines, having a fuel mixture conduit, a spindle journaled transversely of said conduit, an unbalanced valve mounted on said spindle, said valve being adapted to be urged toward closed position by the passage of fuel mixture through said conduit, resilient means acting on said spindle and adapted to urge said valve toward open position, an arm secured on said spindle at a point outside of said conduit, resilient means for urging said arm in valve closing direction, and manually operable means for controlling the action of said second resilient means on said arm.
2. In a governor for internal combustion engines, having a fuel mixture conduit, in combination, an unbalanced valve in said conduit adapted to be urged toward closed position by the passage of fuel mixture through said conduit, resilient means urging said valve toward open position, said resilient means being adapted to substantially balance the closing effort exerted on said valve by the flow of mixture through said conduit at a predetermined engine speed at all positions of said valve, means for adjusting said resilient means to vary said predetermined engine speed, resilient means for urging said valve toward closed position, said second resilient means being of sufficient strength to overcome the effort exerted on said valve by said first resilient means in all positions of said valve, and manually operable means for opposing the effort of said second resilient means.
3. In a governor for internal combustion engines, having a fuel mixture conduit, in combination, an unbalanced valve in said conduit adapted to be urged toward closed position by the passage of fuel mixture through said conduit, resilient means urging said valve toward open position, said resilient means being adapted to substantially balance the closing effort exerted on said valve by the flow of mixture through said conduit at a predetermined engine speed at all positions of said valve, remote control means for adjusting said resilient means to vary said predetermined engine speed, resilient means for urging said valve toward closed position, said second resilient means being of sufficient strength to overcome the effort exerted on said valve by said first resilient means in all positions of said valve, and manually operable means for opposing the effort of said second resilient means.
4. In a governor for internal combustion engines, having a fuel mixture conduit, in combination, an unbalanced valve in said conduit adapted to be urged toward closed position by the passage of fuel mixture through said conduit, resilient means urging said valve toward open po-
- sition, said resilient means being adapted to substantially balance the closing effort exerted on said valve by the flow of mixture through said conduit at a predetermined engine speed at all positions of said valve, means for adjusting said resilient means to vary said predetermined engine speed, resilient means for urging said valve toward closed position, said second resilient means being of sufficient strength to overcome the effort exerted on said valve by said first resilient means in all positions of said valve, and manually operable means for preventing said second resilient means from acting on said valve.
5. In a governor for internal combustion engines, having a fuel mixture conduit, in combination, an unbalanced valve in said conduit adapted to be urged toward closed position by the passage of fuel mixture through said conduit, resilient means urging said valve toward open position, said resilient means being adapted to substantially balance the closing effort exerted on said valve by the flow of mixture through said conduit at a predetermined engine speed at all positions of said valve, resilient means for urging said valve toward closed position, said second resilient means being of sufficient strength to overcome the effort exerted on said valve by said first resilient means in all positions of said valve, and manually operable means for opposing the effort of said second resilient means.
6. In a governor for internal combustion engines, having a fuel mixture conduit, in combination, an unbalanced valve in said conduit adapted to be urged to closed position in response to the passage of fuel mixture through said conduit, means urging said valve toward open position, said means being adapted to substantially balance the closing effort on said valve at a predetermined engine speed at all positions of said valve, and being adjustable to vary said predetermined engine speed, means for adjusting said valve opening means, resilient means for urging said valve toward closed position, and manually operable means for opposing the action of said resilient means.
7. In a governor for internal combustion engines, having a fuel mixture conduit, in combination, an unbalanced valve in said conduit adapted to be urged to closed position in response to the passage of fuel mixture through said conduit, means urging said valve toward open position, said means being adapted to substantially balance the closing effort on said valve at a predetermined engine speed at all positions of said valve, and being adjustable to vary said predetermined engine speed, remote control means for adjusting said valve opening means, resilient means for urging said valve toward closed position, and manually operable means for opposing the action of said resilient means.
